UNITED STATES PATENT OFFICE.

ORRELL ASHTON, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

SHOE-SHAPING MACHINE.

1,175,214.

Specification of Letters Patent.

Patented Mar. 14, 1916.

Application filed December 14, 1910. Serial No. 597,190.

To all whom it may concern:

Be it known that I, ORRELL ASHTON, a citizen of the United States, residing at Swampscott, in the county of Essex and 5 State of Massachusetts, have invented certain Improvements in Shoe-Shaping Machines, of which the following description, in connection with the accompanying drawings, is a specification, like reference characters on the drawings indicating like parts in the several figures.

This invention relates to the manufacture of shoes and is herein shown as embodied in a machine which has been designed particularly for use in shaping turn shoes after the lasting, sewing, shoe turning and re-lasting operations have been performed. These operations leave the shoe upper and the shoe sole in a more or less distorted and 20 rough condition and there is required a large amount of shaping, smoothing and beating out to bring the shoe into conformity with the shape of the last and to impart to both the upper and the sole the 25 smooth and shapely appearance which is demanded in the finished shoe. This work has heretofore been done very largely by hand tools, although machines have been devised for beating out the sole.

30 A general object of the present invention is to provide in a single machine the necessary mechanical devices for performing the several shaping operations required on such a shoe and thus to eliminate the need for 35 using the hand tools heretofore employed.

An important feature of this invention 40 consists in a novel combination of means for beating the side of a shoe, such as a turn shoe or a welt shoe, above the projecting edge portion of the sole or the welt, and means for yieldingly supporting the lower face of said projecting portion of the sole or the welt. As shown said supporting means is depressible to permit the introduction of 45 said projecting portion between it and the beating means and preferably it is constructed or arranged to permit the shoe to be tipped or moved angularly so as to receive the beating action in the welt crease 50 close to the sole and then higher up the side of the shoe for thoroughly shaping the side of the shoe as may be required. The beater receives in operation rapid impulses toward the side of the shoe, and with the 55 shoe positioned as above described the

beater will thus engage the upper face of the projecting edge portion of the sole with rubbing contact while said portion is pressed between the beater and the support. Preferably also the beater receives from its operating means a component of downward movement against the top face of the projecting edge of the sole so as to beat as well as to rub this face.

A further feature of the invention consists in means for engaging the lower face of the projecting edge portion of a shoe sole and rubbing it outwardly toward its edge, and means to assist the operator in positioning the shoe for treatment by the rubbing means. Preferably the positioning means comprises a beater arranged for rubbing engagement with the upper face of the projecting edge portion of the sole or welt while receiving rapid impulses directed inwardly toward the shoe. Preferably also the lower rubbing means comprises a rotary beater which is operative first to beat and then to rub the sole, and the shoe is positioned by the upper beater to receive the beating action of the lower beater over the upper attaching seam.

A further feature of the invention consists in a beating tool having one portion shaped to engage the side of a shoe in and 85 adjacent to the welt crease, and another portion having a beating face of a different contour arranged to be used alternatively for beating a different part of the shoe.

The several features of the invention will 90 be more fully understood from the following description of the machine in which they are embodied and the invention will then be pointed out in the claims.

Figure 1 is a side elevation of a preferred 95 form of the machine; Fig. 2 shows a modified construction; Fig. 3 is an end view from the left of Fig. 1 illustrating the formation of two of the rotary beating tools; Fig. 4 shows a side elevation, partly in section, of 100 a different beating tool; Fig. 5 is a similar view of another beating tool; Fig. 6 shows a modification; Fig. 7 is a side elevation of one of the upper beating tools arranged in combination with a bottom beating tool; 105 Fig. 8 is a perspective view of the parts shown in Fig. 7.

The machine comprises a head or frame 2 supported on the post 4 at an elevation which is convenient for the operator in pre- 110

senting a shoe to the several tools while standing in working relation in front of the machine. The frame has bearings for a main shaft 5 which is driven from a belt 6. 5 This shaft is shown as carrying, in Fig. 1, the large rotary beating tool or beating-out roll 10 and the smaller beating-out roll 12. The larger roll has a peripheral formation which is transversely convex and which 10 comprises a plurality of concentric sole rubbing faces 14. Between these concentric rubbing portions are beating portions formed by two plane or flat faces 15 meeting in an angle at 16. The effect of this 15 formation on a shoe sole presented against the driven roll is to rub by the surface 14, then strike or impart a blow by the first surface 15, then have a scraping action by the angular face 16 followed by a blow by 20 the second face 15 and then a rub by the next face 14. The small beating out roll 12 has a convex periphery formed by alternate concentric portions and flat portions. The 25 peripheral speed of this small roll is of course substantially less than that of the large roll which latter effects the more severe beating while the former is used for finishing the stock.

In the construction shown in Fig. 2 the 30 shaft 5 carries a drum 20, see also Figs. 7 and 8, around the periphery of which are arranged a series of spindles 22 carrying narrow rings 24 the axial openings through which are of larger diameter than the spindles whereby the rings are made to extend 35 out by centrifugal force when the drum is driven by the shaft and to yield inwardly as they strike the work. This construction is fully described and is claimed in my 40 prior Patent No. 1,030,837, granted June 25, 1912. For some classes of work this beater gives most desirable results but I have found that in other classes of work, particularly on small shoes and on shoes 45 where the sole is soft or much moistened, the beating-out action by this roll is more severe than is desirable and better results are obtained by the use of the rolls 10 and 12. In connection with this beater, however, 50 I have herein shown a construction of side beater or upper beacking mechanism which possesses features of novelty and a substantial degree of merit. This mechanism is a further development of the mechanism 55 shown in my prior Patent No. 1,019,878, granted March 12, 1912. In this construction, as herein shown, an auxiliary shaft 25 driven from a belt 23 has a cam 26 for engaging a slide 28 that is supported in a 60 downwardly and forwardly inclined guide 30 whereby said slide normally stands out of the path of the cam but may be moved into the path of the cam by the work and may then receive from the cam impulses of 65 high frequency for acting on work with

light rapid beating blows. A stop 27 held in position by a clamping screw 29 serves to limit adjustably the movement of the slide toward the cam. The beating tool 32 is, in accordance with this invention, 70 adjustably mounted by means of a screw 34 on the slide 28 so that its lower end can be spaced closer to or farther from the path of the rings 24. This arrangement is especially desirable for working upon turn shces 75 in which the beating tool 32 should engage the shoe as closely as possible to the sole which will be inserted in the space between the lower end of the tool and the rings 24. Also in this construction, the slide 28 has 80 erected thereon or formed integral therewith a beating plate 35 the acting face of which is substantially more concave than the concave acting face of the beater 32 whereby said member 35 may more effectually beat the upper over the top face of the toe. An important characteristic of the operation of this mechanism, as shown in Figs. 2, 7 and 8, is that the edge portion of the shoe sole is supported on its upper face 90 against the lower end face of the beater 32 while the lower face of the sole is being beaten, or more strictly speaking, is being rubbed toward its edge by means of the rolls 24. The arrangement is such that the shoe 95 will normally be so held tangentially to the periphery of the ring beater that the rings will strike the shoe bottom at some distance backwardly from the edge of the sole and preferably substantially over the seam by 100 which the sole and upper have been connected. By this means a local beating of the shoe bottom over the seam is effected for flattening the seam against the bottom face of the last. The side beater 32 serves 105 as the guide for the shoe to cause the beating action to take place at this distance from the edge of the shoe. After the rings strike the shoe they glide along the surface until they pass from under the shoe sole at its 110 edge. This gives to the marginal portion of the shoe sole a rubbing and smoothing action while the upper face of the sole margin is supported against the beater 32. Co-incident with this rubbing of the sole margin 115 the vibration of the beater 32 effects a rubbing and a smoothing of the upper face of the sole margin.

In Figs. 1, 5 and 6 the ring beater 20 is replaced by a work supporting table 40 120 yieldingly mounted in an arm 42 to permit depression by the shoe for the purpose of introducing the edge portion of a sole between the table and the beater 32. It will be noted that the yielding quality of this 125 table by which the sole edge may be properly positioned and then held up against the lower end face of the beater for receiving the smoothing action which follows from the reciprocatory movement of said beater 130

is similar in its nature to the yielding support furnished by the rings of the ring beater 20. The reciprocating beater 32 is shown in these figures as extended upwardly 5 above the slide 28 and provided with a second beating face 35' corresponding with the beating face of the member 35 shown in Figs. 2, 7 and 8. In this construction the beater 32 is adjustably held on the slide 28 10 by a clamping screw indicated at 31. In Fig. 6 the table 40 is formed as a plate that is hinged at its rear edge and yieldingly up-pressed by a plunger 44 so that the table fol- 15 lows the shoe as the heel end of the shoe is tipped upwardly for extending the action of the beater 32 higher up along the upper from the plane of the sole. It is also to be noted that in the construction shown in Fig. 20 6 the plane of the lower end face of the beater 32 and likewise the plane of the table and the shoe sole is at a substantial angle to the plane in which the slide 28 reciprocates so that said beater 32 has in effect a down- 25 ward, as well as forward, component of movement toward the shoe and so effects a slight downward beating upon the upper face of the margin of the sole.

The shaft 5 supports a cam 45, Figs. 1 and 4, and the frame has a bearing stud 30 46 from which is pivotally suspended an arm 48 that has on its lower end a vertically concaved beater 50 the heel of which may, by pressure of said shoe against the beater, be forced into contact with the cam 45. The arm 48 is normally held yieldingly away 35 from the cam 45 by an adjustable eccentric 52 carried by the frame and a spring pressed plunger 54 carried by the arm 48. The beater 50 is shaped at its lower portion to 40 extend deeply into the crease between the upper and the sole for beating out and smoothing any wrinkled or uneven portion of the upper not readily reached by the other beating tools.

45 In Figs. 1 and 2 are shown also portions of a novel heating mechanism which is disclosed in detail and claimed in my prior U. S. Patent No. 1,048,637, granted Dec. 31, 1912.

50 Having thus described my invention, what I claim as new and desire to secure by Letters Patent of the United States is:—

1. A shoe shaping machine having, in combination, means for supporting the lower face of a projecting edge portion of a shoe bottom, a beater for engaging the upper face of said edge portion, means for relatively pressing said support and beater together in the direction of the thickness of 55 the said edge portion, and means for operating said beater to cause it to move from and toward the side of the shoe in rubbing contact with the upper face of said edge portion.

60 2. A shoe shaping machine having, in

combination, a yielding support for the sole of a turn shoe and a beater shaped and arranged to permit the edge portion of the sole to be introduced between the support and the lower edge of the beater, and to permit the shoe to be moved angularly to cause the beating action to be received against the side face of the shoe close to the sole and then higher up the side of the shoe. 70

3. A shoe shaping machine having, in combination, a beater shaped and arranged to engage the side of a shoe from the welt crease upwardly, and a support between which and said beater there is capacity for relative movement to permit the introduction between them of the projecting edge of the shoe bottom, said support being arranged to sustain the shoe as it is tipped for causing the beating action to take effect higher or lower on the side of the shoe. 75 80 85

4. A shoe shaping machine having, in combination, a beater shaped and arranged to engage the side of a shoe from the welt crease upwardly, means for imparting substantially right line beating movements to 90 said beater, and a support adapted to permit the shoe to be tipped to cause the beating action to be received against the side face of the shoe close to the sole and then higher up the side of the shoe. 95

5. A shoe shaping machine having, in combination, a beater shaped and arranged to engage the side of a shoe from the welt crease upwardly, shoe supporting means yieldingly pressed toward the beater and de- 100 pressible to permit the introduction of the projecting edge portion of the shoe bottom between the beater and the supporting means, and mechanism for reciprocating said beater, said machine having provision 105 for adjustment of the beater from and toward the supporting means relatively to the beater operating mechanism.

6. A shoe shaping machine having, in combination, a beater shaped and arranged to engage the side of a shoe from the welt crease upwardly, a support for yieldingly upholding the shoe toward the beater and de- 110 pressible to permit the introduction of the projecting edge portion of the shoe bottom between the beater and the support, said beater having a second beating face shaped for engagement with a portion of the shoe which cannot be reached by it while the shoe is rested on the support and means for im- 115 parting reciprocatory movement to said beater toward and from the side of the shoe. 120

7. A shoe shaping machine having, in combination, a beater shaped and arranged to engage the side of a shoe from the welt crease upwardly, and having an upward ex- 125 tension in which is formed a concave beat- ing face shaped to engage a portion of the shoe the contour of which differs from the contour of the shoe near the welt crease, and 130

means for imparting substantial right line reciprocatory shoe beating movements to said beater.

8. A shoe shaping machine having, in combination, a beater shaped and arranged to engage the side of a shoe from the welt crease upwardly, said beater comprising a thin edge shaped to enter the welt crease and a concave face shaped to engage the side of a shoe from the welt crease upwardly and a second face to be used alternatively and shaped to engage a different portion of the shoe, and means for imparting substantially right line reciprocations to the beater.

15. 9. A shoe shaping machine having, in combination, a beater shaped and arranged to engage the side of a shoe from the welt crease upwardly, a support for the projecting edge portion of a shoe bottom, yieldingly movable to permit the shoe to be tipped while it is presented to the beater so as to receive a part of the action of said beater upon the top face of said edge portion, and operating means for imparting to the beater 25 rapid impulses toward the shoe including a component of movement laterally against the side of the shoe and a component of movement downwardly against the top face of the supported edge portion of the shoe bottom.

30. 10. A shoe shaping machine having, in combination, a yieldingly positioned shoe support, a cam, a slide movable automatically away from the cam and toward the support, and a beater having an acting face arranged to be engaged by the side of a shoe rested on the support and shaped to the contour of the portion of the shoe side adjacent to the edge of the shoe and a second acting 35 face arranged above the first one and shaped to the contour of another portion of the shoe, said beater being arranged to cause pressure

of the work against either of said acting faces to move the slide into position to be engaged by the cam for operating the beater. 45

11. A shoe shaping machine having, in combination, means for engaging the upper and the lower faces of the projecting edge portion of a shoe bottom and operating mechanism for causing the means engaging 50 the lower face to rub the lower face outwardly and for imparting to the means engaging the upper face rapid impulses directed inwardly.

12. A shoe shaping machine having, in combination, a beater shaped to engage the upper face of the projecting edge portion of a shoe bottom, and a roll supporting the lower face of said portion of the shoe bottom and rubbing it toward its edge while 60 pressing it yieldingly upward toward the beater.

13. A shoe shaping machine for turn shoes having, in combination, means for engaging the top face of the projecting edge portion 65 of the sole and means for beating the lower face of the sole arranged to strike the sole over the seam that connects the upper thereto and rub the sole from thence toward its edge. 70

14. A shoe shaping machine for turn shoes having, in combination, a rotary beater and means to assist the operator in presenting the shoe to cause the beater to strike the sole over the seam that connects the upper to the 75 sole and to rub from thence outwardly toward the edge of the sole.

In testimony whereof I have signed my name to this specification in the presence of two subscribing witnesses.

ORRELL ASHTON.
